SEPARABLE FASTENER SLIDER LOCK

Davis Marinsky and Louis H. Morin, Bronx, N. Y.

Application April 25, 1942, Serial No. 440,448

7 Claims. (Cl. 24—205.5)

This invention relates to separable fasteners employing sliders movable along the stringers to couple and uncouple the same. More particularly, the invention relates to a slider having a flangless side portion permitting free lateral movement of the links of one stringer therethrough in providing a jam locking of the slider upon the stringers, when the latter are subjected to lateral stresses or strains tending to separate the stringers. The novel features of the invention will be best understood from the following description when taken together with the accompanying drawing, in which certain embodiments of the invention are disclosed, and in which the separate parts are designated by suitable reference characters in each of the views; and in which:

Fig. 1 is a plan view of a sectional portion of a fastener illustrating the slider in locked or jammed position thereon.

Fig. 2 is a perspective view of the slider detached; and,

Fig. 3 is a view similar to Fig. 1 diagrammatically illustrating the slider applied to stringers having straight links.

In various uses of separable fasteners of the kind under consideration, the stringers are subjected to lateral stresses or strains tending to separate the stringers and to move the slider along the stringers and, to check such undesirable separation, automatic locks of various types and kinds have been employed on the slider structure. These locks represent an added cost to the production of the slider and, furthermore, are not entirely fool-proof.

It is the purpose of our invention to provide an economical slider structure which will automatically operate to check accidental opening or separation of the stringers by simply jamming the slider on the links or scoops of the stringers, thus dispensing with the expense of the added parts commonly employed in producing lock sliders not only from the standpoint of the cost of producing the parts, but also from the standpoint of assembling the lock parts upon the slider body.

In Fig. 1 of the accompanying drawing, 5 represents portions of two stringers, on the beaded edges 6 of which are secured links or scoops 7 of the kind having angular offset mounting end portions 8 which produce on the resulting fastener what is termed a herring-bone or chevron effect. This type of stringer construction is shown simply to illustrate one adaptation of the invention.

The slider 9 comprises a top wall 10, a bottom wall 11 spaced from the top wall by a connecting web or frog 12 arranged centrally of the wide end portion of the slider. The frog 12 divides the slider into diverging channels 13, 14 at the wide end portion of the slider, which channels converge into a single channel 15 at the narrow end portion of the slider.

On the top wall 10 is an elongated bar or other member 16 forming means for coupling a finger piece or pull 17 therewith.

The walls 10, 11 have at their peripheral edges of the channeled side 13 thereof short, inturned flanges 18 which extend from the narrow end portion a short distance toward the wide end of the slider leaving a large unchanneled opening 19 between the walls at the wide end portion of the slider. The other side edges of the walls 10, 11 have inturned flanges 20 extended the full length thereof, as is the usual custom. In other words, the flanges 18 are of sufficient length to insure coupling engagement between the links 7 and leave large openings 19 to permit free lateral movement of one of the stringers 5 through the side of the slider, as seen in Fig. 1 of the drawing.

When the stringers 5 are subjected to a stress or strain in the direction of the arrows 21, 22 of Fig. 1 of the drawing, the left hand stringer, as seen in Fig. 1, will extend substantially at right angles to the remainder of such stringer in more or less of a sharp bend; whereas the other stringer assumes a more gradual curve being restricted by the flanges 20. This straining of the stringers operates to tilt the slider body substantially in the manner illustrated in Fig. 1, causing the ends 23 of the flanges 18 to engage one of the links 7 on the left hand stringer, whereas the ends 24 of the flanges 20 engage one of the links of the other stringer, thus jamming the slider against further opening movement longitudinally of the stringers.

It will be apparent that by reason of the free passage of the left hand stringer through the opening 19, the jam locking of the slider on the stringers takes place instantaneously and with a minimum of movement of the slider longitudinally of the stringers. It will also be understood that after the pull or straining has been relieved from the stringers, the slider may be freely moved along the stringers in the usual manner to couple and uncouple the same.

For purposes of description, the slider may be described as having a fully closed channel side 55 and a partially closed or open channel side, one

stringer being freely movable laterally through the opening in said last mentioned side.

The dot and dash line 25, shown in Fig. 1 of the drawing, represents the longitudinal axis of the slider, and with the slider in the tilted position illustrated, it will appear that the stressed left hand end portion 26 of the stringer extends at an angle less than 90° to the center line of the slider considered with respect to the narrow end portion thereof, whereas the strained end portion 27 of the right hand stringer extends at an angle greater than 90° to the slider center as represented by the line 25. Thus it may be said that the slider has a side opening permitting movement of one stringer end to an acute angle relationship with respect to the longitudinal axis of the slider body.

It will, of course, be apparent that the jam lock slider constructed substantially as described is adaptable for use on separable fastener stringers or chains having links or scoops of any desired construction. In other words the conventional straight link of common usage can be employed.

Fig. 3 of the drawing shows diagrammatically the slider arrangement upon conventional straight links, and in this figure, small portions of stringer tapes 28 are shown with straight links 29 thereon illustrating the engagement of the short flanges 30 of the slider 31 with the link of one stringer, as at 32, and the engagement of the longer flanges 33 with the link of the stringer, as at 34.

Having fully described our invention, what we claim as new and desire to secure by Letters Patent, is:

1. In separable fasteners employing stringers, a slider movable along the stringers to couple and uncouple the same, said slider comprising a channeled body having diverging channels at one wide end thereof converging to a single channel at the other narrow end of said body, the stringers having scoops at one edge portion thereof movable through the channels of said slider body in coupling and uncoupling the stringers, means at one side portion of the slider body retaining the scoops within the channel portion of said side throughout the full length thereof, the other side of said body having means at the narrow end portion only thereof for retaining the scoops in the channel of said body, and the remainder of said second named side having an opening permitting free lateral movement of the scoops through said side of the slider body when the stringers are subjected to a stress or strain tending to separate the same.

2. In separable fasteners employing stringers, a slider movable along the stringers to couple and uncouple the same, said slider comprising a channeled body defined by spaced side walls, one side edge portion of the walls of said channeled body having inturned flanges extending throughout the full length thereof, and the other side edge of said walls having inturned flanges extending only part of the length of said edges forming a large opening permitting free lateral movement of one stringer through the second named side edge portion of the slider body.

3. A slider for separable fasteners of the class described, said slider comprising spaced walls joined by a frog portion centrally of the wide end portion of said walls, means at one side por-

tion of the slider forming a continuous channel longitudinally thereof, the other side portion of the slider having means at the narrow end portion only thereof forming a longitudinal channel, and the wide end portion of the second named side of the slider having an opening equal in width to the spacing of inner surfaces of the slider walls.

4. A slider for separable fasteners having series of fastening links mounted on stringers, of the type having a pair of flared walls having side edge portions, wide end portions and narrow end portions, said walls being joined by a web and having a pair of inturned flanges depending from said walls at each side thereof, said walls, web and flanges defining a pair of converging channels, the improvement which comprises a pair of inturned flanges, partly defining one of said channels, depending from said walls at one side thereof and extending throughout the entire length of said channel from the narrow end to the wide end and terminating in lower edges at the narrow end of the slider and upper edges at the wide end of the slider; a pair of flanges depending from said walls at the other side thereof, said flanges extending from the narrow end of the slider and terminating short of the wide end, said first and second named pairs of flanges cooperating upon lateral spreading of the stringers to tilt the slider and lock the same against movement in one direction on the stringers by engagement of a lower edge of the first named flanges with a fastening link.

5. In a slider for separable fasteners, front and back walls, a frog joining said walls at one end portion thereof and forming a pair of diverging channels between said walls, inturned channel side edge portions on opposite sides of said slider, and the channel edge portion of one side of the slider being shorter than at the opposite side thereof.

6. In a slider for separable fasteners of the type having a pair of parallel walls, a frog between said walls forming diverging channels at one end of said slider and a single channel at the other end, inturned edge portions on said walls forming the outer side of each of said channels, the inturned edge portions at one side of the slider extending substantially the entire length of the channel, and the inturned edge portions at the other side of the slider extending for only a part of the length of the channel.

7. In separable fasteners employing stringers having scoops adapted to be coupled and uncoupled, a slider movable along the stringers to couple and uncouple said scoops, a slider having front and back walls, a frog joining the walls at one end and forming a pair of diverging channels between said walls, outer edges of said walls including inturned flanges engaging the scoops of the stringers in coupling and uncoupling said scoops, the inturned flanges or front and back walls at one side of the slider extending the full length of said walls, and the inturned flanges at the other side of said walls extending only part of the length of said sides to provide, in the remaining part of said side of the slider, an opening for free passage of the scoops of one stringer therethrough.
